APPARATUS FOR HANDLING GRANULAR MATERIAL

Reuben T. Savage, Ridley Park, Pa., assignor to
 Houdry Process Corporation, Wilmington, Del.,
 a corporation of Delaware

Application December 15, 1951, Serial No. 261,840

6 Claims. (Cl. 302—17)

1

This invention relates to the handling of granular material, such as contact material in the form of beads or pellets, having a particle size in the range of about 1-15, and preferably about 2-8, millimeters in diameter, employed in the catalytic conversion of hydrocarbons.

The invention is particularly directed to a method and apparatus for transporting the granular material as a continuously moving stream over both an extended lateral or substantially horizontal distance and an extended vertical distance.

The invention finds particular application in the transfer of granular catalyst from point of delivery, such as a railroad siding, directly to the fresh catalyst make-up hopper of a catalytic hydrocarbon conversion unit, such as the type referred to in the article entitled "Houdriflow: New design in catalytic cracking" appearing at page 78 of the January 13, 1949, issue of the "Oil and Gas Journal."

Heretofore it has been a practice when charging the storage hopper of a hydrocarbon conversion unit with fresh make-up catalyst, to unload the catalyst, which is commercially packed in moisture-proof bags, from a railroad car situated at the nearest point of rail delivery, and to transport the bags of catalyst by a separate vehicle to the loading point of an elevator which is especially provided to elevate the catalyst substantially vertically to the catalyst make-up hopper located at a convenient elevation in the conversion system. In many cases, the fresh catalyst must be transported laterally for a distance of several hundred feet between the railroad siding and the engager of the pneumatic lift. The additional handling required, and the extra transporting equipment needed, are obvious disadvantages of such method.

In accordance with the invention, the fresh catalyst is pneumatically conveyed substantially horizontally as a smoothly flowing stream through a tubular conveyor extending laterally from a loading vessel, located at the point of catalyst delivery, to the engager of a pneumatic lift located adjacent to the catalyst make-up hopper, is then carried upwardly through the lift pipe by the same gas which effected its horizontal transportation, with or without the assistance of auxiliary lift gas introduced directly into the lift engager, is disengaged from the gaseous material in known manner at the top of the lift, and is passed by gravity flow into the catalyst make-up hopper.

In a preferred embodiment of the invention,

2

the loading vessel at the inlet end of the horizontal run is located as close to the railroad car or other delivery vehicle as is practicable, so that a minimum of handling may be required in transferring the catalyst from the car to the inlet hopper. The catalyst disengages from the bottom of the loading vessel into the inlet end of the horizontal conduit, or tubular conveyor, where it is engaged by a stream of gaseous material introduced in an amount sufficient to convey the catalyst through the horizontal conveyor to the lift engager without slugging or intermittent flow. It has been observed that during such horizontal movement the catalyst stream has a vertical concentration gradient increasing downwardly, and a vertical velocity gradient increasing upwardly. The pneumatic lift may be of the general type illustrated in the aforementioned article in the "Oil and Gas Journal," with one important difference. Whereas, in a pneumatic lift employed as part of a circulatory system, it was found desirable to maintain a compact moving bed or column of catalyst in the lower region of the engager vessel surrounding a bottom portion of the lift pipe, in the pneumatic lift of the present invention the catalyst introduced into the engager from the horizontal transporting conduit preferably falls freely to the bottom of the engager vessel. The catalyst is then conveyed upwardly through the lift pipe by lift gas comprising essentially the same gas which effected its horizontal transportation. In other words, lift gas may be introduced at the inlet end of the horizontal conveyor in sufficient quantity not only to transport the catalyst the full horizontal distance, but also to elevate the catalyst at the end of its horizontal run upwardly through the vertical lift path. In order to avoid any back-pressure difficulties in the horizontal conveyor when, for any reason, the catalyst accumulates within the engager and tends to form a compact moving bed, a spaced concentric sleeve is provided about the lower end of the lift pipe. The sleeve extends vertically from a point in the upper region of the engager above the level of the catalyst inlet to a point adjacent to the lower end of the lift pipe. The sleeve functions primarily as a safe-guard against flooding of the engager. If the catalyst level within the engager rises a substantial distance above the lower end of the sleeve, the lift gas discharging from the horizontal conduit with the catalyst stream will preferentially disengage itself from the catalyst and, following the path of least resistance, will flow downwardly to the lift inlet through the annular

passage formed between the sleeve and the lift pipe.

While, in most cases, satisfactory operation of the transportation system as a whole may be obtained by introducing all the required lift gas at the inlet end of the horizontal conduit, in some cases it may be desirable to employ a minimum quantity of gas consistent with uniform catalyst flow within the horizontal conduit, which minimum amount of gas may be insufficient to effect the elevation of the catalyst upwardly through the lift pipe. For example, when it is desired to transfer the catalyst from the siding to the catalyst make-up hopper in the shortest possible time, the rate of gas introduction must be increased. At the higher gas input the rate of catalyst flow through the horizontal conveyor may be such as to cause impingement of the discharging stream of catalyst particles against the opposite side wall of the engager. Because of the friable or friable nature of the catalyst, such impingement may cause an undesirable amount of catalyst attrition. In such case, it is contemplated that an additional, but minor, amount of gaseous material may be introduced directly into the engager vessel at any suitable location, preferably at its upper end. This does not, however, preclude the introduction of additional minor amounts of lift gas at other locations within the engager, such as axially below the lift, or laterally of the lower end portion of the lift in the peripheral region of the engager vessel.

Since the present transportation system is not part of the circulatory system of the hydrocarbon conversion unit, there is little reason for providing adjustable control of the catalyst flow rate. The lower end of the lift pipe and the lower end of the sleeve may therefore be set initially at the most suitable level within the engager, which setting should be adequate for all normal operation of the lift.

It is apparent from the foregoing that the lift engager functions as a combination disengager and engager, in that the catalyst may be disengaged from its transporting gas upon introduction into the lift engager, and may subsequently be re-engaged by the same gas, which has been conveyed out of contact with the catalyst to the region immediately surrounding the lift inlet.

For a fuller understanding of the invention reference may be had to the following description and claims taken in connection with the accompanying drawings forming a part of this application, in which:

Fig. 1 is a diagrammatic elevational view of the entire transporting system;

Fig. 2 is a fragmentary elevational view, in partial section, showing the details of the inlet end of the horizontal conveyor;

Fig. 3 is a plan view of the receiving hopper and fragmentary portion of the loading vessel shown in Fig. 2;

Fig. 4 is a sectional view, in elevation, of the lift engager; and

Fig. 5 is a plan view of the lift engager shown in Fig. 4.

Referring to the drawings, the transporting system as a whole is diagrammatically shown in Fig. 1. A loading vessel 11 is located adjacent to a railroad siding some distance from the conversion unit, at which a car 12 containing the catalyst may be parked. A loading platform 13 is provided between the railroad car and the loading vessel to facilitate the manual transfer of bags of catalyst into the receiving hopper 14 of

the loading vessel. The bags may be broken over the edge of the receiving hopper and the contents dumped therein for subsequent discharge into the loading vessel.

The communicating passage between the receiving hopper and the loading vessel is provided with a plug-type closure mechanism, to be fully described hereinafter in connection with Figs. 2 and 3, which controls the admission of catalyst into the loading vessel and provides a pressure seal after loading is completed.

When the loading vessel has been sufficiently charged with catalyst, the plug-type closure member is seated in the discharge opening of the receiving hopper, to provide a pressure seal, and the catalyst is then passed by gravity flow from the lower end of the loading vessel into a horizontal tubular conveyor 16 through a conduit 15, connected to the top of the conveyor tube near its inlet end.

Gaseous material, such as air, is introduced by conduit 17 into the end of conveyor tube 16. As the gas flows past the juncture with conduit 15, it engages the incoming catalyst particles and conveys them through the conveyor tube to a pneumatic lift, generally indicated by the numeral 18. A conduit 19 conveys a portion of the gas from conduit 17 to the upper region of loading vessel 11, so as to equalize the pressure while catalyst is being transferred between the vessel and the horizontal conveyor.

The gaseous material for conveying the granular material is introduced into the conveyor tube in such quantity as to produce the desired characteristics of flow and the desired velocity of discharge into the lift engager. Such gas may or may not, as desired, be sufficient in amount to continue the transportation of the granular material upwardly through the vertical lift. In any event, however, the lift gas comprises all the gas discharged from the horizontal conveyor.

At the discharge end of the horizontal conveyor 16 the catalyst is introduced into the engager vessel 21 of the lift 18 through inlet nozzle 22. Where it enters the engager, the opening of nozzle 22 is vertically elongated, the upper side of the nozzle being horizontal, and the lower side being sloped sharply downward. The incoming stream of catalyst slides down the inclined bottom of nozzle 22 into the engager vessel 21, and falls freely to the bottom. The gas entering the vessel with the catalyst, that is, the same gas which effected its horizontal transportation, carries the falling catalyst, in a reversal of flow, into and upwardly through the vertical lift pipe 23. The flow of catalyst is such that, under normal operation, there is no accumulation of catalyst in the form of a compact moving bed in the bottom of the engager. While it is contemplated that the transporting gas from conveyor 16 may be adequate to elevate the catalyst through the lift pipe, provision is made for the introduction also of additional lift gas into the lift engager 21, to act as auxiliary or supplementary lift gas. Such additional lift gas may be introduced into the upper region of engager 21 through inlet conduit 24.

The stream of lift gas and catalyst discharges from the upper end of the lift pipe 23 into a conventional disengager 25 wherein, in known manner, the catalyst is disengaged from the lift gas. The separated lift gas may be discharged overhead from the disengager 25 to the atmosphere, or it may be passed, as through conduit 26, into the upper end of the catalyst make-up

hopper 21. The disengaged catalyst is collected in the lower region of disengager 25, and is passed by gravity flow through conduit 28 into the upper end of catalyst make-up hopper 21.

Referring to Figs. 2 and 3 of the drawings, the catalyst receiving hopper 14 of the loading vessel 11 is shown as comprising an upper funnel-shaped portion of rectangular cross section and a lower cylindrical portion 29 which extends downwardly through an opening 30 formed in the upper end of the vessel 11. The opening 30 is of greater diameter than the cylindrical portion 29, and is provided with a cylindrical member 31 rigidly secured to the sides of the opening 30. An intermediate flange 32 secured to the portion 29 near its upper end rests upon the upper end of cylindrical member 31. A flat horizontal ring 33 encircles the lower end of portion 29, and is rigidly attached to the lower end of cylindrical member 31. An annular closure seat 34, formed of rubber or other suitable resilient material, is removably secured to the underface of ring 33 by bolts 35.

A closure member comprising a lower conical portion 36 and an upper stem 37 is movably suspended to hang within the cylindrical portion 29 of the hopper 14. The closure member is adapted, when raised to its uppermost position, to seat concentrically within the portion 29, with the upper surface of the conical portion 36 in sealing engagement with the resilient member 34.

A horizontal shaft 38 is provided at the upper rear end of the inlet hopper 14, the ends of the shaft being journaled at 39 and 40 in the side walls of the hopper. One end of shaft 38 extends outwardly from the side of the hopper to receive a handle 41 having a hand grip 42 at its forward end and a counter-weight 43 at its rear end. The handle 41 is rigidly secured to the shaft 38. Parallel link members 44 are rigidly secured at one end centrally along the shaft 38, the link members being spaced sufficiently to receive between their free ends the upper end of stem 37. The stem 37 is pivotally attached to the free ends of link members 44 by a pivot pin 45. The linkage is so arranged that in the closed and the open positions of the closure member the mechanism will be positioned as indicated by the full and the dotted lines, respectively, in Fig. 2.

Referring to Figs. 4 and 5, the lift pipe 23 terminates at a low point within the engager vessel 21, and is surrounded by a spaced concentric sleeve 48 supported at its upper end from the sides of the lift pipe by radial web members 49. The lower end of the sleeve 48 is maintained in concentric position by means of internal spacers 50 attached to the outer surface of the lift pipe. The ends of sleeve 48 are open, thereby forming an annular passage 51 between the lift pipe and the sleeve extending from the upper region of the engager vessel to a point adjacent the lower end of the lift pipe.

Normally, it is expected that immediately after its free fall to the lower region of the engager vessel 21 the catalyst will be conveyed into and upwardly through the lift pipe, without first forming a compact moving bed in the lower region of the engager. The gas entering the engager through nozzle 22 flows in part with the catalyst to the bottom of the engager and in part free from the catalyst downwardly through the annular passage 51. If, at any time, the lift does not elevate the material as fast as it is received, the catalyst may accumulate as a compact bed at the bottom of the engager. In such case, there will be a preferential flow of the

major portion of the lift gas downwardly through the annular passage 51, by reason of the difference in pressure drop through the annular passage and through the compact moving bed. The lift pipe 23 is eccentrically positioned within the engager 21, as shown in Fig. 5, so that it will not be in the way of the stream of catalyst entering through nozzle 22. Thus, the catalyst may, by reason of its momentum, be projected horizontally across the engager vessel and be distributed uniformly over the bottom. In order to prevent severe impingement of the catalyst particles against the wall of engager 21 opposite to the inlet 22 when the system is operating at a high rate of flow, the gas flow in conveyor 16 may be diminished and auxiliary lift gas may be introduced into the upper end of the engager 21 through inlet line 24. With the use of auxiliary lift gas introduced through line 24, the rate of gas introduction at the inlet end of the horizontal conveyor may be sufficient only to provide a uniform flow of catalyst through the horizontal conveyor.

In order to remove catalyst from the lift when the latter has been shut down, a drain outlet 52 is provided at the bottom of engager vessel 21.

In a commercial application of the invention, a 4-inch diameter horizontal conveyor tube was employed in conjunction with a 5-inch diameter vertical lift pipe in an arrangement similar to that illustrated in Fig. 1. A supply of new bead catalyst was transported from a railroad siding 298 feet horizontally and then 173 feet vertically to the fresh catalyst make-up hopper of a catalytic hydrocarbon conversion unit. The average operating conditions are summarized below:

Air mass rate (horizontal) ...	3.61 lb./sq. ft./sec.
Catalyst mass rate (horizontal) ...	42.1 lb./sq. ft./sec.
40 Pressure drop:	

Total	12.0 p. s. i.
Horizontal	8.0 p. s. i.

Under the above conditions, satisfactory operation of the transporting system as a whole was obtained. Precaution must be taken, however, to avoid flooding of the horizontal conveyor with catalyst. Despite the fact that at the air rates employed it was probable that stratified flow of catalyst occurred in the horizontal tube, there was no serious attrition problem. If stratification is considered undesirable in a particular case, however, it may be overcome by increasing the air rate until the stratification ceases and the catalyst flows smoothly in dispersed phase.

Such commercial application has indicated that, in transporting catalyst beads horizontally in accordance with the present invention, only negligible additional catalyst attrition can be attributed to the horizontal conveyor over that obtained by other transporting means.

Obviously many modifications and variations of the invention as hereinbefore set forth may be made without departing from the spirit and scope thereof, and therefore only such limitations should be imposed as are indicated in the appended claims.

What is claimed is:

1. Apparatus for pneumatically conveying solid granular material from a supply point to a laterally and vertically remote receiving point comprising: a loading vessel at said supply point adapted to contain a mass of said granular material, a substantially horizontal tubular conveyor extending from a point adjacent to said

loading vessel to a point substantially vertically below said receiving point, means for introducing gas into the inlet end of said horizontal conveyor, means for withdrawing said granular material from said loading vessel and for introducing the same into said horizontal conveyor beyond the point of gas introduction, a lift engager vessel in open communication with the outlet end of said horizontal conveyor, a lift pipe extending from a level within said lift engager substantially below said outlet end of the horizontal conveyor upwardly to said receiving point, a spaced sleeve surrounding the lower end portion of said lift pipe, said sleeve having its lower end adjacent to the lower end of said lift pipe and its upper end in open communication with the region of said lift engager above said outlet end of said horizontal conveyor, a lift disengager vessel at the upper end of said lift pipe, and means for conveying said granular material 20 by gravity flow from said lift disengager to said receiving point.

2. Apparatus as defined in claim 1 including means for introducing additional gas into said lift engager vessel to supplement the gas discharging from said horizontal conveyor in transporting said granular material into and through said lift pipe.

3. Apparatus as defined in claim 2 in which said means for introducing additional gas into 30 said lift engager is located in the upper region

thereof above said outlet end of said horizontal conveyor.

4. Apparatus as defined in claim 1 including means for pressurizing said loading vessel.

5. Apparatus as defined in claim 1 in which said horizontal conveyor discharges radially into said lift engager vessel, and in which said lift pipe and its surrounding sleeve is eccentric with respect to the axis of said lift engager vessel, and is substantially removed from the discharging stream of granular material.

6. Apparatus as defined in claim 5 in which the discharge end portion of said horizontal conveyor is of gradually increasing flow area, the increase in said flow area being solely in a downward direction.

REUBEN T. SAVAGE.
